BUTTONHOLE-SEWING MACHINE.

1,343,337.

Specification of Letters Patent. Patented June 15, 1920.

Original application filed December 18, 1915, Serial No. 67,683. Renewed April 17, 1920. Serial No. 374,748. Divided and this application filed June 11, 1917. Serial No. 173,914.

To all whom it may concern:

Be it known that I, FRANKLIN A. REECE, a citizen of the United States, residing at Hopkinton, county of Middlesex, State of Massachusetts, have invented an Improvement in Buttonhole-Sewing Machines, of which the following description, in connection with the accompanying drawing, is a specification, like characters on the drawing representing like parts.

This invention relates to buttonhole sewing machines and particularly to the mechanism for cutting the buttonhole. The object of the invention is to provide a novel buttonhole cutting mechanism which is operative to cut the buttonhole while the work is in stitching position thus obviating the necessity of moving the work from stitching position into another position to permit the buttonhole to be cut. Other objects of the invention are to provide a novel mechanism for actuating the buttonhole cutter, and otherwise to improve buttonhole cutting devices, all as will be more fully hereinafter described.

In order to give an understanding of my invention I have illustrated in the drawings a selected embodiment thereof which is designed for use in connection with a sewing machine such as illustrated in my co-pending application Ser. No. 67,683, filed December 18, 1915, and renewed April 17, 1920, as Serial No. 374,748, and of which the present application is a division, but I would state that the invention is not limited in its use to a sewing machine of this particular type.

In the drawings, Figure 1 is a side view of a sewing machine equipped with my improved buttonhole cutter;

Fig. 2 is an underside plan view;

Fig. 3 is a vertical central sectional view of the head of the sewing machine on an enlarged scale;

Fig. 4 is a sectional view through the clutches for operating the stitching mechanism and the buttonhole-cutting mechanism;

Fig. 5 is a section on the line 5—5, Fig. 4;

Fig. 6 is a section on the line 6—6, Fig. 4;

Fig. 7 is a section on the line 7—7, Fig. 4;

Fig. 8 is a fragmentary detail view of the means for controlling the operation of the buttonhole cutter.

1 indicates a base frame on which is supported a bed plate 2 that carries the work 55 clamp 9 and from which rises the overhanging arm 3 carrying the upper thread-handling mechanism, as usual in sewing machines of this type. This upper thread-handling mechanism is in the form of the 60 usual vertically-reciprocating needle bar 4 carrying at its lower end an eye-pointed needle 5. The under thread-handling mechanism is in the form of a rotary element 65 which rotates in a track formed in the casting 7 situated beneath the bed plate 2, as usual in some types of buttonhole sewing machines.

Both the upper and under thread-handling mechanisms are operated from a driving 70 shaft 24 situated beneath the bed plate and which is driven from a driving pulley 181. This shaft 24 is shown as having a spiral gear 47 fast thereon which meshes with a gear 46 fast on a vertically-extending shaft 75 44. The shaft 44 is connected by means of gears 43, 42 to a shaft 36 from which the needle bar 4 is reciprocated, said needle bar being connected to a crank 38 on said shaft by means of a link 39. The rotary element 80 of the under thread-handling mechanism is given its rotation by means of a shaft 142 which is geared to the shaft 44 by means of bevel gears 140, 141.

The work clamp 9 is carried by a clamp 85 plate 8 which is mounted for to-and-fro movement in the bed plate 2 thereby to provide for feeding of the work during the stitching operation. This to-and-fro movement is given to the clamp plate 8 by means 90 of a feed cam 25 which is situated co-axially with the shaft 24 and is driven from the shaft by some suitable mechanism similar to that illustrated in my above-mentioned application, but which it is not necessary to 95 describe herein in detail as it forms no part of the present invention.

The feed cam is provided with a feed cam groove 26 in which is received a roll or projection on the end of an arm 28 pivoted to 100 the frame at 29, said arm 28 having rigid therewith an extension 30 which is pivotally connected to the clamp plate 8 by the link 31, this being the construction shown in my above-mentioned application. As the feed 105 cam 25 rotates, the cam groove will give an

oscillating movement to the elbow-lever 28, 30, thus moving the clamp plate 8 forwardly and backwardly. The parts thus far described are or may be all as illustrated in my said co-pending application and form no part of the present invention.

The buttonhole cutter for cutting the buttonhole is shown at 169 and it is so constructed that it is operative to cut the buttonhole while the latter is in stitching position. In other words, with this invention it is not necessary to shift the work from the sewing position into another position in order to cut the buttonhole.

The buttonhole cutter is shown as sustained by a holder 170 which is situated in an inclined position and slides through a bearing 171 carried by the overhanging arm 3. When the buttonhole cutter is raised, as shown in Fig. 3, it is entirely out of the way of the stitching mechanism, but when it is depressed, the cutting edge of the cutter moves down into position to cut the buttonhole, while the work is still in stitching position, this being the result of the inclined position of the holder 170.

The buttonhole cutter is given its cutting movement by means of an eccentric 172 mounted on the shaft 24, provision being made for clutching the eccentric to the shaft at the time that the buttonhole is to be cut, as will be presently described.

The eccentric 172 is provided with an eccentric strap 178 having an arm 177 extending therefrom which is pivotally connected to one end of a link 176, the other end of said link being connected to a rocking member 174 which is pivoted on the stud or shaft 175. This rocking member has a link 173 pivotally connected thereto at 80, said link being pivotally connected at 81 to the upper end of the holder 170. The link 176 is also pivotally connected to one end of an arm 179, the other end of which is pivoted at 180 to the overhanging arm 3 of the machine frame.

The rotation of the eccentric 172 will give a rising and falling movement to the eccentric strap 178 and its arm 177, and this vibrating movement will be communicated through the link 176 to the rocking member 174 and from the latter to the holder 170. I will preferably so design the overhanging arm 3 that the link 176 and rocking member 174 are inclosed within said arm and the only part of the buttonhole-cutting mechanism which is exposed is the cutter 169. The link 176 and arm 179 constitute a sort of toggle lever construction by which the cutter can be actuated with considerable force.

I have herein provided means whereby the buttonhole cutter can be operated either before the stitching operation commences on a buttonhole or after the stitching operation on said buttonhole is completed. Where the

device is arranged to cut the buttonhole after the stitching is completed, I will preferably so construct the operating mechanism that the buttonhole cutter will be actuated automatically at the proper time in the cycle of 70 operations.

I have stated previously that the shaft 24 from which the stitch-forming mechanism is operated is driven by the driving pulley 181, a suitable clutch being provided for clutching the driving pulley to the shaft when the stitching is to be performed. I have also provided means for clutching the eccentric 172 to the pulley 181 at a time when the shaft 24 is unclutched therefrom so that the buttonhole cutter will be actuated from the driving pulley 181, and the means for accomplishing this is such that the eccentric cannot be clutched to the driving pulley 181 while the shaft 24 is clutched thereto. The two clutches herein illustrated for clutching the shaft 24 and the eccentric 172 to the driving pulley 181 are similar to each other and I will first describe the means for clutching the driving pulley 181 to and unclutching it from the shaft 24.

The pulley 181 is shown as provided with a flange 182, the interior surface 183 of which constitutes a clutch surface, and this clutch surface coöperates with a friction clutch 184 which is carried by a clutch sleeve 185 slidably mounted on the shaft 24. Said clutch sleeve is shown as provided with a laterally-extending pin 186 on which the clutch 184 is mounted. The clutch 184 is an inside expanding clutch and it is clutched to the clutch surface 183 by expanding it. This expansion of the clutch is secured by a clutch-expanding cam 187 rotatably mounted on a pin 188 carried by the sleeve 185. Said cam has a finger 189 extending therefrom which coöperates with a cam 190 formed on the hub 191 of the pulley 181. The pulley 181 is rotating continuously. The clutch sleeve 185 is movable longitudinally of the shaft, and when it is moved inwardly toward the pulley, the clutch finger 189 is brought into the path of the cam 190, and as the pulley rotates, the cam will engage the finger, thereby turning the clutch-expanding cam 187 and expanding the clutch into clutching engagement with the interior clutch surface 183 on the pulley. The pulley will thus become locked to the clutch and thereby drive the clutch sleeve 120 185. Since the clutch sleeve is splined to the shaft 24, the shaft will be thus driven from the clutch sleeve. The clutch sleeve is actuated by a clutch-actuator 192 in the form of a lever pivoted to the frame at 193 and having a forked end 194 which engages pins 296 extending from a ring 195 that loosely encircles the clutch sleeve and engages a collar 297 fast thereon. It will thus be seen that by shifting the clutch sleeve 130

185 to the right, Figs. 2 and 4, the pulley will be clutched to the shaft 24. To unclutch the pulley from the shaft 24, the sleeve 185 is shifted to the left, Figs. 2 and 5 4, thereby to withdraw the finger 189 from the cam 190, and as soon as this is done, the resiliency of the clutch ring 184 will withdraw it from clutching engagement with the surface 183.

10 I have provided herein automatically-operative means for shifting the clutch sleeve 185 into clutch-engaging position, which means is normally held inoperative by a latch so that to start the machine it is only necessary to release the latch and allow the automatically-operative means to throw the clutch into engagement. I have also provided automatically-operative means to positively disengage the clutch at the end of 15 the stitching operation. The automatically-operative means for throwing the clutch into engagement is herein shown in the form of a spring 196 which surrounds the shaft 24 and engages at one end against the bearing 197 for said shaft and at the other 20 end against the sleeve 185. This spring is normally held inoperative by a latch 198 pivoted to the bed plate at 199 and provided with a hook 200 adapted to engage 25 the end of the lever 192, thereby to hold the clutch disengaged, as shown in Fig. 2. This lever 192 has a link 201 connected thereto which is pivoted to a clutch-disengaging lever 202 that in turn is pivoted at 203 to 30 the frame of the machine and is provided with a nose 204 adapted to be engaged by a stop cam 205 mounted on the cam element 25. This stop cam 205 is shown in dotted lines Fig. 2 because it is on the back side of 35 the cam element 25. The cam element 25 rotates in a direction so that when the stop cam 205 is on the back of the cam element looking at Fig. 2, said stop cam is moving toward the top of Fig. 2, and in its upward 40 movement, it engages the end 204 of the lever 202, thereby swinging said lever in the position shown in Fig. 2 and operating through the link 201 and clutch actuator 192 to disengage the clutch. The stop cam 45 205 is so positioned on the cam element 25 that the clutch will be disengaged at the completion of the buttonhole. The latch 198 is acted upon by a spring 206 which 50 operates to throw it into engagement with the lever 192 when the clutch has been disengaged by the stop cam 205 and thus the clutch is locked in its disengaged position. To start the machine again the latch 198 is 55 turned against the spring 206 to release the clutch actuator 192, thereby allowing the clutch 60 actuator 192 to throw the clutch into engagement.

While any suitable means may be employed for releasing the latch I have shown 65 herein a starting lever 207 pivoted to the

bed plate 2 and connected by a flexible connection 209 which passes around suitable friction pulleys 210 to the end of the latch 198 so that depression of the starting lever 207 will release the latch and allow the 70 clutch to be thrown into engagement.

As stated above, the buttonhole cutter 169 is also actuated from the driving pulley 181 and the means I have herein provided for operating it is such as to cause 75 said cutter to operate either before the stitching is begun or after the stitching on the buttonhole has been completed. The eccentric 172 is carried on a sleeve 219 which is loosely mounted on the shaft 24 and is 80 adapted to be clutched to the flange 61 of the pulley 181. The clutch I have herein shown for this purpose is similar to that above described for clutching the shaft 24 to the flange 182 of the pulley 181. The 85 flange 61 is provided with an interior clutch surface 220 which is adapted to be engaged by an expanding clutch ring 221 similar to the clutch ring 184. This clutch ring is expanded into clutch-engaging position by a 90 clutch-operating cam 87 loosely mounted on a stud 88 carried by a clutch sleeve 222 that is splined to the sleeve 219. The clutch-operating cam 87 is provided with an arm 89 which is adapted to be brought into engagement with the cam 90 on the hub 62 of the pulley 181 when the clutch sleeve 222 is moved to the left, Figs. 2 and 4. The action of the cam 90 against the arm 89 will expand the clutch member 221 and thus clutch 95 the sleeve 219 to the driving pulley. Movement of the clutch sleeve 222 to the right, Figs. 2 and 4 will carry the arm 89 out of engagement with the cam 90, thus releasing 100 the clutch. The clutch sleeve 222 is acted 105 upon by a spring 223 which tends normally to throw it into clutching position, and the movement of the clutch sleeve is controlled by a clutch-actuating lever 224 which is pivoted at 225 and provided with a forked end 110 94 engaging pins 95 extending from a ring 242 that is loosely mounted on the clutch sleeve 222 and engages a collar 243 fast thereon. This lever 224 is connected by a link 226 to a controller lever 227 pivoted to 115 the frame at 228 and having at its end a roll 229 adapted to be engaged by a stop cam 230 rigid with the sleeve 219. The lever 224 is acted upon by a latch 231 which 120 normally holds the clutch 221 disengaged, and this latch has a tail 331 which is connected by a flexible connection 232 to a controlling lever 233 similar to the starting lever 207. When the controlling lever is 125 depressed, the latch 231 is released thereby allowing the spring 223 to throw the clutch 221 into engagement, and when this occurs the sleeve 219 will be rotated from the driving pulley thereby actuating the buttonhole cutter. As the sleeve completes one rotation 130

the stop cam 230 engages the roll 229 and operates the controlling lever 227 to disengage the clutch 221.

I have provided herein means whereby the clutch 221 for operating the buttonhole cutter is automatically engaged at the time that the clutch 184 for driving the shaft 24 is disengaged, so that as soon as the stitching operation is ended, the buttonhole will be automatically cut. This is herein provided for by providing the latch 231 with a pointed nose 234 and by providing a resilient arm 235 which is secured to the link 201, said arm 235 being so constructed that when the link 201 is moved to the left, Fig. 2, at the time that the clutch 184 is thrown into clutching engagement, said arm will wipe over the nose 234, while when the link 201 moves to the right, Fig. 2, as it does when the stop cam 205 becomes operative to disengage the clutch 184, said arm will engage the flat side of the nose 234 and thereby swing the latch 231 downwardly so as to release it from the lever 224. When this occurs, the spring 223 will operate to throw the clutch 221 into engagement, thus setting the buttonhole cutter in operation.

240 is an elbow-lever pivoted to the frame at 236, said lever carrying a roll 238 adapted to engage a block 239 which is carried by the link 226. This lever is acted upon by a pulling spring 237. The purpose of this lever is to disengage the finger 235 from the nose 234 as the clutch 221 is being engaged so as to permit the latch 231 to become operative automatically when the clutch 221 is disengaged again at the end of the button-hole-cutting operation. When the stop cam 205 actuates the lever 202 and moves the link 201 to the right, Fig. 2, thereby to disengage the clutch 184, the resilient finger 235 acts against the nose 234, as above described, to release the latch 231 from the lever 224, and at this time the resilient arm 235 is carried over the end 241 of the lever 240. As soon as the latch 231 is released the spring 223 will throw the clutch 221 into engagement and this operation will cause the link 226 to move to the right. Such movement of the link 226 will cause the block 239 to engage the finger 238 and thus turn the lever 240 clockwise about its pivot 236. This movement of the lever 240 brings the end 241 thereof against the resilient arm 235 and raises said arm out of engagement with the tail 234, thus allowing the latch 231 to resume its operative position. When, therefore, the buttonhole has been cut and the clutch 221 has been disengaged again, the latch 231 will be operative to hold the clutch 221 disengaged until the time comes for cutting the next buttonhole in the succeeding cycle of operations.

I have herein provided a stop device to insure the bringing of the sleeve 219 to rest

at a predetermined point when the clutch 221 is disengaged. This stop device is shown in Fig. 6 and comprises a stop lug 211 on a plate 212 secured to the clutch-actuating sleeve 222, and a stop dog 213 which is slidably mounted in a stand 214 carried by the frame and backed by a spring 215. The stand 214 is so situated that when the clutch sleeve 222 is in the clutch-disengaged position the stop dog 213 will be in the path of movement of the stop lug 211, but when the clutch sleeve 222 is moved to the left, Fig. 4, to cause the clutch to be engaged, then the stop lug 211 is carried laterally out of engagement with the stop dog 213. The direction of rotation of the shaft 24 is indicated by the arrow in Fig. 6 and it will be observed that when the clutch is disengaged and the clutch sleeve 222 has been moved so that the stop dog 213 will be in the path of movement of the stop lug 211, then said stop lug will be brought into engagement with the stop dog at a predetermined point in the rotation of the sleeve 219, said stop dog acting to bring the sleeve to rest with a yielding or cushioned movement. In order to prevent any rebound, I have provided herein a dog 217 pivoted at 218 to the stand 214 and acted upon by a spring 216. When the stop lug 211 moves around into engagement with the stop dog 213, it will wipe by the dog 217 and the latter will snap in behind the lug and thus prevent any rebound after the parts have been brought to rest.

I claim:

1. In a buttonhole sewing machine, the combination with a frame having an overhanging arm, of a buttonhole-cutting element slidably mounted on the arm, a rocking member connected to said cutting element, a toggle element comprising two members pivotally connected together, one member being pivotally connected to said rocking member and the other member being pivoted to said overhanging arm, and means acting on said toggle element between its ends, thereby to oscillate the rocking member.

2. In a buttonhole sewing machine, the combination with a frame having an overhanging arm, of a buttonhole-cutting element slidably mounted on the arm, a rocking member connected to said cutting element, a toggle element comprising two members pivotally connected together, one member being pivotally connected to said rocking member and the other member being pivoted to said overhanging arm, a driving shaft, and a cam member thereon arranged to act on said toggle element between its ends.

3. In a buttonhole sewing machine, the combination with a frame having an overhanging arm, of a buttonhole-cutting ele-

ment slidably mounted on the arm, a rocking member connected to said cutting element, a toggle element comprising two members pivotally connected together, one member being pivotally connected to said rocking member and the other member being pivoted to said overhanging arm, a driving shaft, an eccentric thereon, an eccentric strap encircling said eccentric and connected to said toggle element between its ends.

4. In a buttonhole sewing machine, the combination with a frame having an overhanging arm, of a holder slidably mounted in said arm, a buttonhole cutter carried by said holder, a rocking member pivotally mounted on said arm and connected to said holder, a toggle device comprising two pivotally connected members, one of which is pivotally connected to the rocking member, a driving shaft, and an eccentric connected to said toggle device between its ends.

5. In a buttonhole sewing machine, the combination with stitch-forming mechanism, of a buttonhole cutter, a driving pulley, driving connections between said pulley and said stitch-forming mechanism, a clutch for connecting said connections to or disconnecting them from the driving pulley, clutch-controlling mechanism for disconnecting the clutch upon the completion of a buttonhole, actuating mechanism for the buttonhole cutter, a second clutch for connecting said actuating mechanism to or disconnecting it from the driving pulley, means controlled by said clutch-controlling mechanism to render the second clutch operative when the first-named clutch is disengaged thereby to cause the buttonhole cutter to cut a buttonhole, and means to disengage said second clutch when the cutting on the buttonhole has been completed.

6. In a buttonhole sewing machine, the combination with stitch-forming mechanism, of buttonhole-cutting mechanism, a driving shaft connected to the stitch-forming mechanism, a pulley on said shaft, a sleeve loosely mounted on said shaft and connected to the buttonhole-cutting mechanism, means to clutch the pulley to and unclutch it from the shaft, and means operative automatically to clutch said sleeve to said pulley when the pulley is unclutched from the shaft.

7. In a buttonhole sewing machine, the combination with stitch-forming mechanism, of buttonhole-cutting mechanism, a driving shaft for operating the stitch-forming mechanism, a driving pulley loosely mounted thereon, means to clutch the driving pulley to and unclutch it from the shaft, actuating mechanism for the buttonhole-cutting mechanism, a clutch situated co-axially of said shaft and adapted to connect said actuating mechanism to the pulley,

and means operative automatically to actuate said clutch when the driving shaft is unclutched from the pulley.

8. In a buttonhole sewing machine, the combination with stitch-forming mechanism, of buttonhole-cutting mechanism, a driving shaft for operating the stitch-forming mechanism, a driving pulley loosely mounted thereon, a clutch by which said driving pulley is clutched to and unclutched from said shaft, clutch-controlling mechanism for disconnecting said clutch upon the completion of a buttonhole, actuating mechanism for the buttonhole-cutting mechanism, a second clutch situated co-axially of said shaft for connecting said actuating mechanism to said driving pulley, and means to actuate said second clutch when the driving shaft is unclutched from the pulley.

9. In a buttonhole sewing machine, the combination with stitch-forming mechanism, of buttonhole-cutting mechanism, a driving shaft for operating the stitch-forming mechanism, a driving pulley loosely mounted thereon, a clutch to clutch the driving pulley to and unclutch it from said shaft, clutch-controlling mechanism for disconnecting the clutch upon the completion of a buttonhole-actuating mechanism for the buttonhole-cutting mechanism, a second clutch situated co-axially of said shaft for connecting said actuating mechanism to said pulley, and means controlled by said clutch-controlling mechanism to actuate said second clutch when the driving shaft is unclutched from the pulley.

10. In a buttonhole sewing machine, the combination with stitch-forming mechanism, of buttonhole-cutting mechanism, a driving pulley, driving connections between said pulley and said stitch-forming mechanism, a clutch for connecting said connections to or disconnecting them from the driving pulley, other driving connections between said pulley and said buttonhole-cutting mechanism, a second clutch for connecting said other connections directly to or disconnecting them from the driving pulley, and automatic means to render said second clutch operative when the first-named clutch is disengaged.

11. In a buttonhole sewing machine, the combination with stitch-forming mechanism, of buttonhole-cutting mechanism, a driving shaft connected to the stitch-forming mechanism, a driving pulley loosely mounted on the shaft and having two clutch flanges, a sleeve mounted on said shaft and connected to the buttonhole-cutting mechanism, a clutch co-operating with one of said clutch flanges to connect the pulley to the shaft, another clutch co-operating with the other clutch flange to connect said pulley to the sleeve.

12. In a buttonhole sewing machine, the

- combination with stitch-forming mechanism, of buttonhole-cutting mechanism, a driving shaft connected to the stitch-forming mechanism, a driving pulley loosely mounted on the shaft and having two clutch flanges, a sleeve mounted on said shaft and connected to the buttonhole-cutting mechanism, a clutch coöperating with one of said clutch flanges to connect the pulley to the shaft, another clutch coöperating with the other clutch flange to connect said pulley to the sleeve, and means operative automatically to render the second clutch operative when the first clutch is disengaged.
13. In a buttonhole sewing machine, the combination with stitch-forming mecha-

nism, of actuating means therefor including a clutch, clutch-controlling mechanism for disconnecting the clutch upon completion of a buttonhole, buttonhole-cutting mechanism, a clutch for actuating said buttonhole-cutting mechanism, means controlled by the clutch-controlling mechanism to render said second clutch operative when the first-named clutch is disengaged thereby to cause the buttonhole-cutting mechanism to cut a buttonhole, and means to render said second clutch inoperative when the buttonhole has been cut.

In testimony whereof I have signed my name to this specification.

FRANKLIN A. REECE.
